UNITED STATES PATENT OFFICE.

CHARLES MEISSNER, OF SAN DIEGO, CALIFORNIA, ASSIGNOR OF ONE-THIRD TO
CHARLES R. ROBINSON, OF SAN DIEGO, CALIFORNIA.

GENERATING-BURNER MECHANISM FOR GASOLINE LANTERNS.

Application filed March 5, 1925. Serial No. 13,266.

To all whom it may concern:

Be it known that I, CHARLES MEISSNER, a citizen of the United States, residing at San Diego, in the county of San Diego and 5 State of California, have invented a certain new and useful Generating-Burner Mechanism for Gasoline Lanterns, of which the following is a specification.

My invention relates to that class of gasoline lanterns which has the burner located 10 above the gasoline receptacle.

It is well known, by those versed in the art, that there is always a quantity of vapor which is inflammable present in the space 15 above the gasoline in gasoline receptacles.

The objects of my invention are:

First, to provide a means for utilizing the vapor in the receptacle for furnishing fuel to the burner of gasoline lanterns until the 20 burner shall become sufficiently heated to generate the gas from the gasoline itself, thus eliminating the necessity of having to heat the generator or feed pipe with a blow torch or other independent heating means.

Second, to provide a novel initial burner means for heating the gasoline tube preparatory to its generating its own gas from the gasoline.

Third, to provide an initial burner means 30 of this class in which the vapor from the gasoline receptacle is properly distributed and burned for heating the gasoline conducting tube to the burner.

Fourth, to provide a novelly constructed 35 initial generating burner means for gasoline lanterns, and—

Fifth, to provide a means of this class which is very simple and economical of construction, durable, efficient and which will 40 not readily deteriorate or get out of order.

With these and other objects in view as will appear hereinafter, my invention consists of certain novel features of construction, combination and arrangement of parts 45 and portions as will be hereinafter described in detail and particularly set forth in the appended claims reference being had to the accompanying drawings and to the characters of references thereon, which form a part 50 of this application in which:

Figure 1 is a side elevational view of a gasoline lantern showing my generating burner mechanism in connection therewith, and showing certain parts and portions

broken away and in section to facilitate the 55 illustration, and Fig. 2 is a longitudinal sectional view of the burner generating apparatus on an enlarged scale.

Similar characters of reference refer to similar parts and portions throughout the 60 several views of the drawings.

The gasoline receptacle 1, valve casing 2, thimble member 3, gasoline conducting tube 4, spring coil 5, nut 6, air tube 7, and burner 8, constitute the principal parts and portions 65 of my gasoline lantern generating burner mechanism.

The gasoline receptacle 1 is of the ordinary or conventional type provided with an internally threaded orifice in the central 70 upper portion and is provided with the usual pressure pump 1^a therein. Secured in the orifice 1^a is the valve casing 2 and it is provided with two ports therethrough, the one extending from the upper portion of the receptacle through the casing and to one side of the upper side of the casing 2, while the other extends from near the bottom of the receptacle 1 to a central portion in the upper portion of the casing 2. This casing 75 is provided with a central extending portion 2^a over which the lower end of the gasoline conducting tube 4 is mounted and is secured in position by means of the nut 6 screwed onto the extended portion 2^a so that the orifice 2^b in the casing 2 is for conducting the gasoline upwardly to the tube 4 where it is generated into vapor and conducted to the burner 8. The casing 2 is provided with an externally threaded portion 2^c over which 80 is mounted a thimble member 3, the walls of which converge upwardly forming a taper at the upper end, as shown best in Figure 2 of the drawings. This is provided with screw threads at its lower end adapted 85 to fit over the portion 2^c. It is provided with a plurality of air inlet orifices 3^a at its lower end to admit air to mix with the vapor from the upper portion of the receptacle 1 passing through the port 2^d in the casing 2. Wound around the gasoline conducting tube 4 is a spring member 5 which fits snugly the tube 4 to near the upper end 90 of the thimble member 3 and then is wound outwardly and downwardly in spiral form so that it engages with the tapered portion of the thimble member 3 and when the thimble member 3 is screwed onto the casing mem-

95

ber 2 spreads the spiral portion and serves as a mixer for the vapor and air which passes out at the upper end of the thimble 3 where it is ignited and heats the tube 4 until the tube 4 is sufficiently heated to generate its own vapor from the gasoline from the receptacle 1. When the valve is turned it closes the port 2^a and opens the port 2^b.

Though I have shown and described a particular construction, combination and arrangement of parts and portions I do not wish to be limited to this particular construction, combination and arrangement but desire to include in the scope of my invention the construction, combination and arrangement substantially as set forth in the appended claims.

Having thus described my invention what I claim as new and desire to secure by Letters Patent is:

1. In a gasoline lantern, a valve casing, a gasoline conducting tube communicating with one of the ports in said casing, a thimble mounted on said casing around said tube and provided with an inwardly tapered upper end and provided with a plurality of air inlet ports near its lower end; said valve casing provided with a port communicating with the interior of said thimble at its lower end between the gasoline conducting tube and said thimble and a wire coil positioned around said gasoline conducting tube and provided with a spiral portion, the outer side of which engages the tapering portion of said thimble.

2. In a generating burner mechanism for gasoline lanterns, a valve casing with two ports therethrough, a gasoline conducting tube communicating with one of said ports, a thimble surrounding said gasoline tube, the interior of which communicates with the other port in said valve casing and a metallic

coil member interposed between said thimble and said gasoline conducting tube.

3. In a generating burner mechanism for gasoline lanterns, a valve casing with two ports therethrough, a gasoline conducting tube communicating with one of said ports, a thimble surrounding said gasoline tube, the interior of which communicates with the other port in said valve casing and a metallic coil member interposed between said thimble and said gasoline conducting tube and means for admitting air to the lower end of said thimble above the communicating port in said casing.

4. In a generating burner mechanism for gasoline lanterns, a valve casing with two ports therethrough, a gasoline conducting tube communicating with one of said ports, a thimble surrounding said gasoline tube, the interior of which communicates with the other port in said valve casing and a metallic coil member interposed between said thimble and said gasoline conducting tube and means for admitting air to the lower end of said thimble above the communicating port in said casing and valve means for regulating the flow of vapor or gasoline through said valve casing.

5. In a mechanism of this class described, a valve casing with two ports, one for gasoline and the other for vapor, a tube communicating with the gasoline port, a thimble member surrounding said gasoline tube and communicating with the vapor port and a metallic coil wound around said gasoline tube and a portion engaging the upper portion of said thimble member whereby the members of said coil are spread.

In testimony whereof, I have hereunto set my hand at San Diego, California, this 13th day of February, 1925.

CHARLES MEISSNER.
